D11-26. OR D11-767 EX

UNITED STATES PATENT OFFICE.

CHARLES Z. DE YOUNG, OF PHILADELPHIA, PENNSYLVANIA.

DESIGN FOR A RING.

SPECIFICATION forming part of Design No. 11,767, dated May 11, 1880.

Application filed April 3, 1880. Term of patent 7 years.

To all whom it may concern:

Be it known that I, CHARLES Z. DE YOUNG, a citizen of the United States, residing in the city and county of Philadelphia, and State of Pennsylvania, have invented and produced a new and original Design for a Piece of Jewelry known as a "Finger," "Scarf," or other Ring, of which the following is a specification, reference being had to the accompanying photographic illustration, forming part thereof.

A represents the head or body of the piece, and B the ring, to which the head is attached, said head being in the form of a miniature lo-

comotive-engine, and produces a neat and attractive design, suggestive of the business of engineers and other employés of railway companies, &c.

I claim—

The design for a jewelry-ring, consisting of the head or body A, of the form of a miniature locomotive-engine, and the connected ring B, as shown and described.

C. Z. DE YOUNG.
